UNITED STATES PATENT OFFICE.

GUY B. SIMPSON, OF VENETIA, PENNSYLVANIA.

RIM EXPANDER.

Application filed July 12, 1921. Serial No. 484,252.

To all whom it may concern:

Be it known that I, GUY B. SIMPSON, a citizen of the United States, residing at Venetia, in the county of Washington and State of Pennsylvania, have invented new and useful Improvements in Rim Expanders, of which the following is a specification.

This invention relates to expanding devices, and more particularly to a device for expanding automobile rims.

One of the main objects of the invention is to provide a device of the character stated of simple construction and operation which may be readily applied to a rim of standard construction. A further object is to provide a device in which the pressure will be exerted in such direction as to expand the rim so as to bring the ends thereof into contact, the pressure applying means being readily adjustable to suit circumstances. Further objects will appear from the detailed description.

In the drawings:

Figure 1 is a side view of an expander constructed in accordance with my invention.

Figure 2 is a top plan view of the same taken substantially on line 2—2 of Figure 1.

Figure 3 is a side view of the device as applied.

The device comprises two substantially circular bands 1 which are secured in parallel spaced relation by connecting strips 2. Each of these bands is provided adjacent to each end with a plurality of sleeves 3 which

are secured to the inner face of the band transversely thereof. These sleeves are disposed in pairs transversely of the device and are adapted to receive pins 4 inserted

through the sleeves and through eyes 5 of

eye bolts 6 upon which a turn buckle 7 is

threaded, the shanks of these bolts being oppositely threaded.

By turning the turn buckle 7 in one direction the members 1 may be compressed or moved toward each other

45 at their free ends so as to permit ready insertion of the device in rim a upon which a

tire b has been placed. By rotating turn buckle 7 in such direction as to force the

bolts 6 apart the device is spread so as to

50 expand the rim a until the inner end a'

thereof contacts with the outer end a''. The

pins 4 and sleeves 3 provide simple and

efficient means whereby the bolts 6 and turn buckle 7 may be adjusted so as to insure application of the pressure along a line disposed at such an angle to the rim as to expand the rim with a minimum of force applied.

The position of the opening provided in the rim to accommodate the valve stem often varies considerably in rims of different makes relative to the cut or opening of the rim. For this reason, when the rim is applied, the valve stem may be in any one of a number of different positions relative to the cut or ends of the rim. In some rims the valve stem is positioned diametrically opposite to the break in the rim, and in others it may be positioned one-quarter, or more or less, of the circumference of the rim from the cut or break in the rim. In some makes of rims, such as the Stanweld and Baker rim, knobs or projections are provided on the inner face of the rim. By providing the two spaced annular members or bands 1, 75 I produce an expander which may be readily used with a rim of any type, as the bands straddle the valve stem or projections on the inner face of the rim thus permitting the device to be so placed that the ends of 80 the bands are positioned adjacent to the ends of the rim. This insures that the pressure for expanding the rim is applied to the very best advantage so as to permit the rim to be readily expanded with but little effort. 85

What I claim is:—

1. In a device of the character described, two annular members secured in parallel spaced relation, and means adjacent to the ends of said members for expanding and contracting the same.

2. In a device of the character described, two substantially annular members secured in parallel spaced relation, sleeves secured to the inner faces of said members adjacent to the ends thereof and disposed transversely of the members, oppositely threaded eye bolts, pins passing through said sleeves and the eyes of the bolts for adjustably attaching the same to said members, and a turn buckle threaded upon said bolts.

In testimony whereof I affix my signature.

GUY B. SIMPSON.
